ILLUMINATED, TRANSLUCENT, COLORED
DOME**

Otto R. Scheurer, Fort Wayne, Ind., assignor to Tokheim
Corporation, Fort Wayne, Ind., a corporation of Indiana

Application January 18, 1956, Serial No. 39,836

Term of patent 7 years

(Cl. D52—2)

Fig. 2

Fig. 1

Figure 1 is a perspective view of the fuel dispenser, illustrating one of the dial sides and the hose side, showing my new design.

Figure 2 is a top plan view thereof.

The opposite sides of the dispenser, not shown, are all substantially similar to the corresponding sides which are shown and the essential features of the design reside in the solid line portions.

I claim:

The ornamental design for a motor fuel dispenser with internally illuminated, translucent, colored dome, as shown and described.
